PORTABLE BURIAL VAULT

Harold F. Harris, Durhamville, N. Y., assignor to
 Maxwell Steel Vault Company, Oneida, N. Y., a
 corporation of New York

Application April 30, 1934, Serial No. 723,217

11 Claims. (Cl. 27—35)

This invention relates to a portable burial vault for receiving and retaining a burial casket with or without a body therein preparatory to transportation or shipping.

5 The main object is to provide simple and efficient means whereby the casket may be easily and quickly but firmly nested and secured within the vault in balanced relation thereto so that the vault with its contents may be more conveniently handled or transported from one place to another with less liability of impairment of those units than has heretofore been practised.

10 In other words, I have sought to prevent any appreciable relative horizontal or vertical movement of the casket and vault when assembled in the manner hereinafter described during such handling or transportation.

15 One of the specific objects is to mount the casket centrally upon a suitable supporting base or frame and to enable said frame with the casket thereon to be inserted through the open end of the vault along and upon the bottom thereof with a sliding motion and interlocked therewith against relative vertical, lateral or horizontal movement and thereby to assure a fixed balanced relation between the casket and vault.

20 Another specific object is to provide means, preferably in the form of cleats secured to the upper surface of the frame in such relation as to hold the casket centrally on the frame against relative horizontal movement.

25 Another object is to provide the frame with suitable straps adapted to be passed around the top of the casket to hold the latter against vertical movement relatively to the frame.

30 Another object is to provide means whereby the rear end of the casket-supporting frame will be automatically interlocked with the corresponding end wall of the vault against relative vertical movement.

35 A further object is to provide releasable means whereby the front end of the casket-supporting frame may be conveniently and expeditiously locked and released to and from the bottom of the vault.

40 Other objects and uses relating to specific parts of the invention will be brought out in the following description.

In the drawing:—

45 Figure 1 is a perspective view partly in section, of a sheet metal burial vault and the casket-supporting frame with the casket thereon in operative position within the vault, one end of the vault being open to permit the insertion and removal of the casket and its supporting frame.

50 Figure 2 is a perspective view, partly in section and partly broken away, of the lower portion of the vault showing more particularly the locking flange on the rear end wall and the threaded sockets near the front end of the vault for receiv-

ing the locking means for the front locking bar.

Figure 3 is a perspective view, partly broken away, of the detached casket-supporting frame.

Figure 4 is an enlarged detail sectional view through the front end of the bottom wall and device for locking the corresponding end of the frame in operative position.

Figure 5 is an enlarged vertical sectional view of the lower rear end of the vault and adjacent portion of the casket-supporting frame together with the locking device for the rear end of the frame.

5 In order that the invention may be clearly understood, I have shown a portion of a sheet metal vault 1 open at one end and adapted to be closed by a suitable door, not shown, said vault comprising, in this instance a substantially flat bottom portion 2, opposite side portions 3, an end portion 4 and a top portion 5, all of which are firmly united at their junctions one with the other to form a rigid and substantially rectangular structure.

10 The rear end wall 4 is provided with a flange or bar 6 preferably in the form of an angle iron welded or otherwise permanently secured to the inner face thereof to project inwardly therefrom in spaced relation to and parallel with the bottom 1 to form a groove 7 having a vertical depth substantially equal to the thickness of the casket-supporting base or frame, presently described.

15 A pair of similar internally threaded bosses or nuts 8 are welded or otherwise rigidly and permanently secured to the upper face of the bottom 1 near the front end thereof to project upwardly therefrom and are arranged in a transverse plane 35 parallel with the rear bar 6, said nuts being spaced apart transversely relatively to each other and to the side walls 3 of the vault to register with lengthwise openings in the casket-supporting frame previously mentioned.

20 A casket-supporting frame 9 carrying a casket A is inserted through the open end of the vault 1 along and upon the upper face of the bottom 2 to cause its rear end to enter the groove 7 in such manner that the flange or bar 6 will be in 45 overhanging engagement with the upper face of the adjacent end of the frame 9, as shown in Figures 1 and 5.

25 This frame 9 preferably consists of a plurality of, in this instance three, parallel boards or strips 50 10 arranged in transversely spaced relation to form intervening lengthwise slots or openings 11 extending from end to end of the frame and adapted to receive the threaded bosses or nuts 8 when the frame with the casket thereon is inserted into the vault, the width of the frame being approximately equal to the distance between the side walls 3 which, together with the threaded bosses or nuts 8, serve to hold the frame and vault 55 against relative lateral movement.

A pair of lengthwise cleats 12 are secured by screws or other fastening means 13 to the upper face of the frame 1 in parallel transversely spaced relation a distance apart corresponding approximately to the width of the bottom of the casket A, said cleats being preferably arranged equal distances from the longitudinal center of the frame to hold the casket centrally on the frame against relative lateral movement thereon.

10 An additional pair of end cleats 14 are secured by screws or equivalent fastening means 15 to the upper surface of the frame 9 to extend transversely thereof in parallel spaced relation a distance apart corresponding to the length of the 15 bottom of the casket A to hold the latter against relative endwise movement thereon, said cleats 14 being arranged approximately equal distances from the ends of the frame for holding the casket midway between the end walls of the vault when 20 the frame with the casket thereon is nested within in said vault in the manner shown in Figure 1.

The frame 9 is of greater length than the bottom of the casket A to extend approximately equal distances beyond the opposite ends of said 25 casket when the latter is placed in operative position upon the frame between the end cleats 14 which are also arranged substantially equal distances from the ends of the frame to hold the casket centrally on the frame to balance the load 30 carried by the frame.

The fixed nuts 8 are arranged a distance from the rear end 4 of the vault slightly less than the length of the frame 9 and are registered with the corresponding lengthwise openings 11 between 35 the slats or strips 10 so that when the frame with the casket thereon is placed in operative position within the vault with its rear end underlying the flange or bar 6, the nuts 8 will be close to the front end of the frame but still in the 40 adjacent ends of the openings 11, as shown more clearly in Figure 4, thus permitting the use of suitable means for locking the front end of the frame to the bottom of the vault to cooperate with the rear end of the vault for holding the 45 frame against relative endwise movement.

This locking means preferably consists of a cross bar 16 and a pair of clamping bolts 17, the bar 16 being preferably made in the form of an angle iron with one of its flanges arranged in a 50 vertical plane and secured by screws 18 or equivalent fastening means to the front end of the slats or boards 10 and its other flange extended rearwardly in a horizontal plane in overhanging engagement with the upper surface of the adjacent 55 end of the frame, as shown more clearly in Figure 4.

The overhanging flange as 16' of the locking bar 16 is provided with transversely spaced apertures 18 for receiving the clamping bolts 17 which, 60 together with the apertures 18, are arranged a distance from the rear end edge of the frame 9 corresponding to the distance between the rear end 4 of the vault and threaded sockets 8' of the nuts 8 so that when the frame with the casket 65 thereon is inserted into the vault through the open end thereof and the rear end of the frame is engaged with the end walls 4 of the vault, the clamping bolts 17 will be registered with their respective threaded sockets 8' in the nuts 8, said 70 clamping bolts being then screwed by hand into the nuts and against the upper face of the bar 16 to hold the adjacent end of the frame against vertical movement relatively to the bottom of the vault.

75 A pair of longitudinally spaced straps 19 are

passed transversely around the top and opposite sides of the casket and attached by screws 20 or equivalent fastening means to opposite lengthwise edges of the frame 9, said straps being preferably arranged equal distances from the ends of the casket when the latter is mounted on the frame 9 between the cleats 12 and 14 to hold the casket against vertical movement relatively to the frame. 5

Operation

10 The frame 9, including the cleats 12 and 14 and locking bar 16, are preferably made up as a complete unit ready to receive the casket A which is placed thereon between the cleats 12 and 14 and secured thereto by means of the straps 19 before the frame with the casket thereon is installed in the vault, it being understood that during this installation the clamping bolts 17 will be disengaged from their respective nuts 8 and if desired may be temporarily removed from the 20 bar 16.

When the casket A is mounted on the frame 9 in the manner described, said frame with the casket strapped thereto is inserted through the open end of the vault rearwardly along and upon the bottom 2 with a sliding motion until the rear end of the frame enters the groove 7 in underlying engagement with the fixed cross bar 5, thereby automatically locking the rear end of the frame and vault against relative vertical movement, it 30 being understood that the rear end 4 of the vault serves to limit the rearward movement of the frame 9 at which time the apertures 18 in the front cross bar 16 will be registered with the threaded sockets 8' of the corresponding nuts 8, 35 thus permitting the thumb screws or clamping bolts 17 to be passed through the apertures 18 and engaged with their respective nuts 8 for holding the front end of the frame and vault against relative vertical movement and at the same time holding the frame against accidental forward movement. 40

It will now be understood that when the casket A is mounted on the frame 9, it will be held against relative horizontal movement thereon by 45 the cleats 12 and 14 and will also be held against vertical movement relatively to the frame by means of the straps 19.

It will also be understood that when this frame with the casket thereon is inserted into the vault, 50 it will be held against lateral movement through its engagement with the side walls of the vault and will also be held against endwise movement through the engagement of its opposite ends with the rear wall 4 and front cross bar 16 which, 55 it will be remembered, is secured to the bottom of the vault through the medium of the clamping bolts 18 and nuts 8.

Under these conditions the frame will be held against vertical movement relatively to the bottom of the vault by the overhanging flanges of the cross bars 5 and 16. 60

It is now clear that the casket A with its contents, if any, will be substantially balanced centrally upon the frame 9 and that this frame with the casket thereon when installed within the vault will also be substantially balanced centrally therein, all of which permits convenient handling of the vault and when the open end of the vault is closed the entire assembly may be transported from place to place without liability of relative shifting of the casket or frame within the vault, thus carrying out the main object of the invention. 65

70 It is evident, however, that various changes may 75

be made in the detail construction of the holding means for the frame and casket without departing from the spirit of the invention, it being understood that when the frame 9 with the casket thereon is removed from the vault and the straps 19 are loosened the casket may be readily lifted from the frame out of engagement with the cleats 12 and 14.

When removing the frame with the casket thereon from the vault, it is only necessary to withdraw the two clamping bolts 17 whereupon the frame with the casket thereon may be withdrawn endwise through the open end of the vault after which the straps 19 may be detached from the frame to permit removal of the casket from said frame.

The cleats 12 and 14 and front locking bar 16 are preferably secured permanently to the slats 10 in the manner described, the cross cleats 14 and bar 16 serving to hold the slats in relatively fixed spaced relation.

What I claim is:

1. The combination with a portable burial vault, of a casket-supporting frame movable into and out of the vault, means for securing the casket to the frame, and means secured to one of the walls of the vault to project inwardly therefrom in overhanging engagement with a portion of the frame to assist in holding said frame against upward movement relatively to the bottom of the vault.

2. The combination with a portable burial vault, of a casket-supporting frame movable into and out of the vault, means for securing the casket to the frame, and a bar secured to one of the end walls of the vault to project inwardly therefrom in overhanging engagement with the corresponding end of the frame to assist in holding the frame against upward movement relatively to the bottom of the vault.

3. The combination with a portable burial vault, of a casket-supporting frame movable into and out of the vault, means for securing the casket to the frame, and means releasably secured to the bottom of the vault in overhanging engagement with a portion of the frame to assist in holding said frame against upward movement relatively to the bottom of the vault.

4. The combination with a portable burial vault, of a casket-supporting frame movable into and out of the vault, means for securing the casket to the frame, and a bar releasably secured to the bottom of the vault in overhanging engagement with a portion of the frame to assist in holding the latter against upward movement relatively to the bottom of the vault.

5. The combination with a portable burial vault, of a casket-supporting frame movable into and out of the vault, means for securing the casket to the frame, and cleats on the frame for engaging the sides and ends of the casket for holding the latter against endwise and lateral movement relatively to the frame.

6. The combination with a casket and a portable vault therefor having an opening in one end, of a supporting frame for said casket movable through said opening along the bottom of the vault, means for holding the casket on the frame against relative upward displacement therefrom, and means on the vault for holding the frame against relative endwise and lateral movement.

7. The combination with a casket and a portable vault therefor having an opening in one end, of a supporting frame for said casket movable through said opening along the bottom of the vault, means for holding the casket on the frame

against relative upward displacement therefrom, flanges on the vault in overhanging engagement with opposite ends of the frame for holding the frame against upward displacement relatively to said bottom, and means for releasably securing one of the flanges in place.

8. The combination with a portable burial vault, of means for holding a casket therein against relative movement comprising a frame adapted to rest upon the bottom of the vault and to extend from side to side the greater portion of the length thereof, means attached to the frame to hold the casket against upward displacement therefrom, flanges secured to the vault in overhanging engagement with opposite ends of the frame to hold the latter against upward displacement from the bottom of the vault, and cleats secured to the frame to engage the opposite sides and ends of the casket for holding the latter against horizontal movement relatively to the frame.

9. The combination with a portable burial vault of means for holding a casket therein against relative movement comprising a frame adapted to rest upon the bottom of the vault and to extend from side to side the greater portion of the length thereof, means attached to the frame to hold the casket against upward displacement therefrom, means permanently secured to the vault for engaging one end of said frame to hold the latter against upward displacement from the bottom of the vault, means removably secured to the vault for engaging the opposite end of said frame to hold the latter against upward displacement from the bottom of the vault, and means secured to the frame to engage the opposite sides and ends of the casket for holding the latter against horizontal movement relatively to the frame.

10. The combination with a portable burial vault, of a casket-supporting frame movable into and out of the vault, means for securing the casket to the frame, means secured to one of the walls of the vault to project inwardly therefrom in overhanging engagement with a portion of the frame to assist in holding said frame against upward movement relatively to the bottom of the vault, said frame having longitudinally extending cut out portions, bosses extending upwardly from the bottom of the vault secured to the inner side thereof and adapted to register with said cut out portions when the frame with the casket thereon is slid endwise into the vault, and releasable means extending through the frame into engagement with said bosses to assist in holding said frame against upward movement relatively to the bottom of the vault.

11. The combination with a portable burial vault, of a casket-supporting frame movable into and out of the vault, means for securing the casket to the frame, means secured to one of the walls of the vault to project inwardly therefrom in overhanging engagement with a portion of the frame to assist in holding said frame against upward movement relatively to the bottom of the vault, said frame having a cut out portion, a boss extending upwardly from the bottom of the vault adapted to register with said cut out portion when the frame with the casket thereon is placed in the vault, and releasable means extending through the frame into engagement with the boss on the bottom of the vault to assist in holding said frame against upward movement relatively to the bottom of the vault.
